UNITED STATES PATENT OFFICE.

GRACE ALMEDA BELL, OF LOS ANGELES, CALIFORNIA.

DESIGN FOR A ROBE.

57,198.

Specification for Design.

Patented Mar. 8, 1921.

Application filed September 7, 1920. Serial No. 408,797. Term of patent 8½ years.

To all whom it may concern:

Be it known that I, GRACE ALMEDA BELL, a citizen of the United States, residing at Los Angeles, in the county of Los Angeles and State of California, have invented a new, original, and ornamental Design for a Robe, of which the following is a specification, reference being had to the accompanying drawing, forming a part thereof.

I claim:

The ornamental design for a robe, substantially as shown.

Signed at Los Angeles, in the county of Los Angeles and State of California, this 31st day of August, 1920.

GRACE ALMEDA BELL

Witness:

JAMES R. TOWNSEND.
